United States Patent Office

Des. 211,354
Patented June 11, 1968

211,354

FACSIMILE TRANSCEIVER

Donald L. McFarland and Glenn Reese, Torrance, Calif.,
assignors to The Magnavox Company, Fort Wayne,
Ind., a corporation of Delaware

Filed Aug. 16, 1966, Ser. No. 3,480

Term of patent 14 years

(Cl. D26—14)

Des. 211,354

PAGE 2

Des. 211,354

PAGE 3

FIGURE 1 is a perspective view of a facsimile transceiver or similar article showing our new design;

FIGURE 2 is a front elevation view thereof, the rear being plain and unornamented;

FIGURE 3 is an elevation view taken from one side thereof, the opposite side being a mirror image of the side shown; and,

FIGURE 4 is a top plan view thereof.

The broken line representation of a telephone hand set in FIG. 1 is for purposes of illustration only.

We claim:

The ornamental design for a facsimile transceiver, as shown and described.
